LIQUID DISPENSING APPARATUS

John N. Anagno, Lynn, Mass.

Application February 15, 1938, Serial No. 190,627

7 Claims. (Cl. 225—5)

This invention relates to beverage dispensing apparatus and particularly to apparatus for use in storing and dispensing beer and other carbonated liquids.

The object of the invention is to improve the construction and operation of apparatus of the class referred to, particularly with respect to the manually operated faucet by which the beer or other liquid is drawn from the apparatus; with respect to the control of the pressure and flow of the liquid as it reaches and passes through the delivery faucet during the operation of making a delivery, and with respect to the temperature and pressure at which all of the static liquid contents of the apparatus is normally maintained.

It is also an object of this invention to provide an improved delivery faucet for use in dispensing beer and other carbonated liquids.

To these ends I have provided improvements in apparatus of the class described as set forth in the following description, the several novel features of the invention being separately pointed out and defined in the claims at the close thereof.

In the accompanying drawings:

25 Figure 1 is a central longitudinal sectional view of a delivery faucet constructed in accordance with this invention showing the same mounted in a wall of a refrigerator or the like.

Figure 2 is a section on line 2—2 of Fig. 1.

30 Figure 3 is a section on line 3—3 of Fig. 1.

Figure 4 is a detail hereinafter referred to.

Figure 5 illustrates an alternative construction.

The dispensing apparatus herein illustrated 35 comprises a delivery faucet 10 mounted in the back wall 11 of a refrigerator compartment 11a which may be provided within a bar or counter of which the wall 11 forms part. It is customary to provide a cooling unit (not shown) within the 40 compartment 11a, said unit being controlled and operated to maintain therein a desired predetermined temperature. The compartment 11a is provided for the reception of a barrel containing beer or other carbonated liquid, said barrel 45 being provided with an outlet that is connected with the inlet 12 of the faucet 10 by eight or nine feet of metal tubing 13 having an inside diameter of five thirty-seconds (32) of an inch, or 50 thereabouts.

The improved faucet illustrated in Figs 1 to 4, inclusive, comprises a body consisting of a straight tubular shank 14 to the outer end of which is rigidly attached a hollow head 15 and 55 whose inner end portion is exteriorly threaded

to receive upon it a nut 16 and a coupling member 17.

The shank 14 of the faucet body extends through a hole formed through the rear wall 11 of the refrigerator and is fixedly clamped thereto by means of the nut 16, while the coupling member 17 serves to fixedly clamp the flanged end of delivery tube 13 against the outer face of an abutment annulus or bushing 18 that is tightly fitted within the inner end of the tubular shank 14. The outer end of the tubular shank 14 is formed with a counterbore 19 into which is forcibly fitted one end of a tubular extension 20 formed adjacent to its outer end with a longitudinal slot 21, Fig. 4, that is opened at one end. 10 15

Upon the outside of the extension 20 is telescopically fitted a nozzle element 22 which is free to be moved endwise thereon, the outlet end portion of said element being directed downwardly as shown in Fig. 1. This nozzle element 20 22 has rigidly fixed to it one end of a tube 23 which extends therefrom through slot 21 of extension 20 into the latter and thence longitudinally into the tubular shank 14. 15

Through engagement with the opposite side 25 walls of the slot 21 the tube 23 prevents rotation of the nozzle element on extension 20 but, as will be clear, said nozzle element is free to be moved endwise thereon. In other words the nozzle element and extension are telescopically associated 30 and splined together so that they cannot rotate relatively.

The inner end portion of the tubular shank 14 of the faucet body is made interiorly with a relatively large cylindrical valve chamber 24 35 whose outer end is connected by a relatively small port 25 with the inner end of the extension 20. The difference in the diameters of chamber 24 and port 25 provides an annular shoulder or step which is formed as a seat 26 for an elongate valve 40 member 27 slidably mounted within chamber 24. Normally the elongate valve member 27 is yieldingly urged endwise toward and against seat 26 by a coiled spring 28 disposed within chamber 24 between the abutment annulus or bushing 18 45 and the proximate end of said valve member 27. When the valve member 27 occupies this closed position its outer end is in close proximity to the inner end of the tube 23 and it will therefore be clear that if the delivery nozzle 22 is manually 50 or otherwise forced inwardly on the tubular extension 20 said inner end will engage the valve member 27 and shove the same longitudinally away from its seat 26 thereby opening the faucet and permitting the beer or the like to flow under 55

pressure from tube 13 into chamber 24, around valve member 27 and thence through port 25 and extension 20 into nozzle 22 from which it discharges downwardly into the glass or other vessel 5 placed in position to receive it.

When the nozzle 22 is relieved of the pressure by which it was forced inwardly to open the faucet the pressure of the beer against valve member 27 acts to quickly thrust the latter endwise 10 into position against its seat 26 and during this closing movement of the valve member the latter acts through the tube 23 to quickly return the nozzle 22 to its outermost position again. When the valve member 27 and nozzle 22 are 15 thus snapped back and restored to their normal positions again by the pressure of the beer or the like, the tube 23 serves as a vent through which air is free to pass from the outside atmosphere into the port 25 thereby permitting said 20 port, extension 20 and nozzle 22 to be quickly evacuated or emptied of all beer or the like. This provides a quick draining feature which avoids dripping after delivery and tends to maintain that portion of the interior of the faucet that is outside of valve member 27 sanitarily dry while not 25 in use.

The nozzle 22 is made upon its upper side with an upstanding lug 29, Figs. 1 and 2, to cooperate as an abutment shoulder with a radial arm 30 30 depending from a transversely disposed spindle 31 which extends through, and is journaled in, bearings provided at opposite sides of the hollow head 15 of the faucet body. This spindle 31 is provided with an upwardly extending arm 32 that 35 is outside of the head 15 and which is utilized as a lever by means of which the spindle 31 is manually rotated in a direction to open the faucet. The spindle 31 is secured within the bearings provided for it in the head 15 by means 40 of a nut 33 that is screwed on to the threaded free end of the spindle as shown in Fig. 2. As will be clear the arm 32 and spindle 31 constitute a manually operated nozzle adjusting member or lever, the arm 30 of said member or 45 lever providing a radial abutment shoulder to cooperate with a radial abutment shoulder that is provided on the nozzle by the lug 29.

The elongate valve member 27 is, as shown in Fig. 3, circular or cylindrical throughout the 50 greater portion of its length but its opposite ends are made hemi-spherical so that each of said ends is of streamline form which avoids agitation. Also, the said valve member is slidably supported centrally within the cylindrical chamber 24 by means of a plurality of rails 34 occupying longitudinal grooves formed upon the exterior of the valve member 27. These rails may be short lengths of wire slidably engaging the interior surface of the tubular shank 14 55 and serving to maintain the valve member and the tubular shank 14 relatively concentric with segmental passageways 35 for the beer between said two parts. In other words, the body of the valve member 27 is made less in diameter than the chamber 24 and is maintained concentric with the latter by the rails 34. This provides a 60 flow-retarding constriction within the faucet and surrounding the valve member 27 which, together with the streamline form of the valve member, avoids excessive foam. In practice I have found that for all ordinary pressures under which the beer is delivered, the best effects are secured if the space between the exterior of valve member 65 70 75 27 and the interior of the wall surrounding

chamber 24 measure about fifteen thousands (.015") of an inch.

When the arm or lever 32 is swung downwardly toward the left, Fig. 1, the arm 30 on spindle 31 acts against lug 29 to shove the nozzle 22 inwardly until its movement in that direction is arrested by a resilient abutment ring 36 mounted within the outer end of the tubular shank 14.

The hollow head 15 is made upon its outer side with a cylindrical socket 37 within which is frictionally fitted one end of hood 38 which incloses the delivery end of nozzle 22 but in such manner that the latter is free to be moved back and forth on extension 20 as above described. 10 15

In the form of this invention illustrated in Fig. 5 I provide a coiled spring 39 mounted upon the extension 20 between the outer end of the tubular shank 14 of the faucet body and the inner end of the nozzle 22. The spindle 31 of the nozzle operating lever 32 is formed, outside of hollow head 15, with a flange 40 that is notched to provide two abutment shoulders 41 and 42 to cooperate with a stop pin or stud 43 projecting from head 15. Normally the spring 39 yieldingly holds nozzle 22 at the limit of its movement toward the left in Fig. 5 with shoulder 41 abutting one side of the stop pin or stud 43. To open the faucet the lever 32 is swung downwardly toward the left and its spindle shifts nozzle 22 30 35 inwardly until shoulder 42 engages the pin or stud 43. At the conclusion of the delivery the operator merely releases the lever 32 with the result that the parts are restored to their normal positions by the pressure of the beer acting through the valve member supplemented by the pressure of spring 39 against the inner end of nozzle 22. 40 45 50 55

It will be observed from Fig. 1 that the chamber 24, port 25, extension 20 and nozzle 22 provide the faucet with an approximately straight delivery conduit which is free and clear of abrupt angles which would tend to "cut" the beer and thereby cause foaming and waste. Furthermore, it will be observed that the valve member 27 serves as a pressure reducing valve because of the elongate constricted passageway provided between said member and the surrounding wall of chamber 24. Also, the valve centralizing rails 34 insure proper cooperation between the valve member and its seat at all times and prevent any lateral displacement or fluttering of the valve. 55 60 65 70 75

It is a feature of advantage to the above described ventilating construction that when the nozzle 22 is shoved inwardly the inner end of the vent tube 23 bears against the outer end of the valve member as it pushes the latter into its open position with the result that the inner end of the vent tube 23 is closed by the valve member while a delivery is being made so that the beer is prevented from entering or passing through said vent tube. 80

What I claim is:

1. A liquid dispensing apparatus of the character described comprising a delivery conduit made with an elongate valve chamber of relatively large cross-sectional area and into one end of which beer or the like is supplied under pressure; an outlet port at the opposite end of said chamber; a valve seat within said chamber surrounding the inlet end of said port; an elongate valve member slidably supported independently and centrally within said chamber so that it is movable longitudinally toward and from said seat 65 70 75 80 85 90 95 98 99 100

and normally urged independently endwise against the latter by the pressure of the beer or the like to close said port, the cross-sectional area of said valve member being predeterminedly less than the cross-sectional area of said chamber thereby to provide an elongate constricted pressure-reducing passageway through which the beer or the like is forced from the inlet end of said chamber to said outlet port when said valve member is shifted longitudinally away from said seat, and independently supported means that is manually operable to adjust said member axially away from said seat by abutting engagement with one end of said member thereby to 15 open said port.

2. A liquid dispensing apparatus of the character described constructed in accordance with claim 1 and wherein a plurality of longitudinal supporting rails are provided between said valve 20 member and the wall of said delivery conduit to maintain said member centrally disposed within said conduit.

3. A liquid dispensing apparatus of the character described comprising a delivery conduit 25 made with an elongate valve chamber of relatively large cross-sectional area and into one end of which beer or the like is supplied under pressure; an outlet port at the opposite end of said chamber; a valve seat within said chamber surrounding the inlet end of said port; an elongate valve member slidably supported independently and centrally within said chamber so that it is movable longitudinally toward and from said seat and normally urged independently endwise 30 against the latter by the pressure of the beer or the like to close said port, the intermediate portion of said valve member being cylindrical, the opposite ends of said valve member being hemi-spherical, and the cross-sectional area of 35 said valve member being pre-determinedly less than the cross-sectional area of said chamber thereby to provide an elongate constricted pressure-reducing passageway through which the beer or the like is forced from the inlet end of 40 said chamber to said outlet port when said valve member is shifted longitudinally away from said seat, and independently supported means that is manually operable to adjust said member axially away from said seat by abutting engagement 45 with one end of said member thereby to open said port.

4. A faucet of the character described comprising a body including a tubular shank having an inner end portion formed interiorly with a valve 50 chamber of relatively large cross-sectional area to the inner end of which beer or the like is supplied under pressure; means for securing said

shank to a supporting fixture; an outlet port at the outer end of said chamber; a valve seat within said chamber surrounding the inlet end of said port; an elongate valve member slidably supported centrally within said chamber so that it is movable longitudinally toward and from said seat and normally urged endwise against the latter by the pressure of the beer or the like to close said port, the cross-sectional area of said valve member being predeterminedly less than the 5 cross-sectional area of said chamber thereby to provide an elongate constricted pressure-reducing passageway through which the beer or the like is forced from the inlet end of said chamber to said outlet port when said valve member is shifted longitudinally away from said seat; a nozzle element telescopically engaged with and splined to said body, and into which the beer or the like is delivered from said outlet port, said nozzle member being slidable on said body 10 toward and from said valve member; means carried by said nozzle element and extending into said outlet port so as to engage and open said valve member when moved inwardly with said nozzle element, and means through which said nozzle element is manually shifted inwardly thereby to open said valve member and effect delivery of beer or the like from said nozzle.

5. A faucet of the character described constructed in accordance with claim 4 and wherein the means carried by said nozzle element through which the latter acts to open said valve member when shifted inwardly, consists of a vent tube whose inner end communicates with the interior of said body adjacent to the outer end of said 20 valve member and whose outer end communicates with the outside atmosphere.

6. A faucet of the character described constructed in accordance with claim 4 and wherein said last mentioned element of claim 4 consists of a 25 lever pivotally supported by said body and cooperatively associated with said nozzle element so that when swung in one direction said element is adjusted inwardly to open said valve.

7. A faucet of the character described comprising a body having a delivery conduit extending therethrough; means for securing said body to a supporting fixture; a valve member adjustably mounted within said conduit for controlling the latter; a nozzle element movably mounted 30 upon said body into which the beer or the like is delivered from said conduit when said valve is open, and means through which movement of said nozzle element on said body operates said valve.

JOHN N. ANAGNO.
